UNITED STATES PATENT OFFICE.

ELOF PEHRSON, OF LETHBRIDGE, ALBERTA, CANADA.

DOOR-OPERATING MECHANISM.

1,087,820.

Specification of Letters Patent.

Patented Feb. 17, 1914.

Application filed July 13, 1912. Serial No. 709,181.

To all whom it may concern:

Be it known that I, ELOF PEHRSON, a subject of the King of Great Britain, residing at Lethbridge, in the Province of Alberta 5 and Dominion of Canada, have invented new and useful Improvements in Door-Operating Mechanism, of which the following is a specification.

This invention relates to improvements in 10 furnace doors and especially with reference to means for opening furnace doors so as to avoid the necessity of putting down a shovel, loaded with coal, before opening a furnace door preparatory to throwing the 15 coal in the furnace, the object of the invention being to provide an improved furnace door operating means of this character which is extremely cheap and simple, is strong and durable, is not likely to get out of 20 order and which may be installed on any furnace of ordinary construction.

The invention consists in the construction, combination and arrangement of devices hereinafter described and claimed.

25 In the accompanying drawing:—Figure 1 is an end elevation of a portion of a furnace provided with doors and door operating devices constructed in accordance with my invention. Fig. 2 is a horizontal section view of the same on the plane indicated by the line *a—a* of Fig. 1, showing the door closed in full lines and open in dotted lines.

For the purposes of this specification, a 30 portion of the front end or casing of a furnace is indicated at 1, the door opening being indicated at 2 and the ash door being indicated at 3. A door frame 4 is bolted or otherwise secured on the front side of 35 the wall 1 and extends around the door opening 2. On this frame is the lower door 5 and the upper door 6 which are respectively provided at one end with hinges 7—8. Each door is provided in its opposite 40 end and preferably near its upper side with a recess 9. Latches 10, to engage the inner side of the door frame 4 are provided with stems 11 which are pivotally mounted in 45 openings with which the furnace doors are provided and at the outer ends of the said stems are operating arms 12 which project from the free ends of the furnace doors, the 50 inner ends of the said operating arms being mounted in the recess 10 and bearing on 55 the bottom of said recess. Each stem 11 is

provided with a shoulder 13 which engages the inner side of one of the furnace doors.

An eye bolt 14 projects from the outer side of each furnace door, near the hinged end thereof and springs 15, which are connected 60 to the furnace wall or front 1, as at 16 are connected also to the said eye bolts 14, the said springs acting to open the furnace doors.

When the doors are closed, they are held 65 in closed position by the gravitating action of the operating arms 12 of the latches, the said operating arms normally holding the latches engaged with the inner side of the door frame 4. A vertically movable op- 70 erating bar 17 is mounted in guides 18 on the outer side of the door frame 4 and near the free ends of the doors 5—6. This operating bar is provided with a series of openings 19 and is also provided with tappet 75 pins 20 which may be placed and are adjustable in the said openings and are so arranged as to bear respectively under the lower sides of the operating arms 12 of the latches. A pedal 21 is provided with a ver- 80 tical arm 22 which is arranged to operate in a guide 23. A lever 24 is pivotally mounted as at 25, has one end pivotally connected as at 26 to the upper end of the pedal arm and has its opposite end connected piv- 85 otally as at 27 to the lower end of the operating bar 17. The weight of said operating bar is such that it is normally in lowered position, shown in Fig. 1, and with its tappet pins just below the operating arms 12, 90 the pedal being held normally in elevated position. The doors are normally closed as shown in Fig. 1 and also as shown in full lines in Fig. 2. In order to open the doors, it is only necessary to place one foot on the 95 pedal 21 and depress the same, thus causing the lever 24 to raise the operating bar 17. The upward movement of the operating bar causes its tappet pins to engage the lower sides of the operating arms 12 to raise the 100 outer ends of said operating arms, thus causing the stems of the latches to turn so that the latches disengage the inner side of the door frame 4 and, hence, the furnace 15, when the doors are thus released, operate to 105 open the doors, as indicated in dotted lines in Fig. 2. This renders it unnecessary for the person who attends the furnace to place a shovel loaded with coal on the floor before 110 opening the furnace door. If it is desired

that only one of the furnace doors shall be opened by the operating mechanism, the tappet pin which operates the latch arm of the other door can be removed from the operating bar 17.

While I have herein shown and described a preferred form of my invention, I would have it understood that changes may be made in the form, proportion and construction of the several parts, without departing from the spirit of the invention and within the scope of the appended claims.

I claim:—

1. A furnace wall having a door opening, 15 a door frame on the wall and having a door opening of less length than that of the opening in the wall so that one end of the door frame projects inwardly in and partly covers the opening in the wall, a door 20 hinged at the other end of the frame, and a latch on the inner side of the door at its free end, arranged to engage the inner side of the said projecting end of the door frame, and said latch having a stem extending 25 through and pivotally mounted in an opening in the door, and an operating arm at the outer end of said stem acting by gravity to hold the latch in fastened position.

2. A furnace having a door frame, a door hinged at one end of the door frame, a latch 30 carried by the other end of the door, adapted to engage the corresponding inner side of the door frame when the door is in closed position and having a stem pivotally mounted in the door and an operating arm 35 at the outer end of the said stem on the outer side of the door, said operating arm acting by gravity to normally hold the latch in fastened position, a vertically movable operating bar mounted on the front side of 40 the door frame and having a tappet pin movable with said bar to engage and actuate the latch arm, said tappet pin being below the latch arm when the bar is in normal depressed position, a lever mounted on the 45 front side of the furnace and pivotally connected to the operating bar, and a pedal having a vertical arm connected at its upper end to the said lever to operate the latter.

In testimony whereof I affix my signature in presence of two witnesses.

ELOF PEHRSON.
